TAPE CUTTING DEVICE

Filed Dec. 29, 1949.

UNITED STATES PATENT OFFICE

2,655,214

TAPE CUTTING DEVICE

Paul Van Cleef, Los Angeles, Calif.

Application December 29, 1949, Serial No. 135,767

5 Claims. (Cl. 164—84.5)

1

The present invention relates generally to devices for cutting tape. More particularly the invention relates to that type of device which is specifically designed for use with tape in roll form, i. e., tape that is wound in spiral form around an annular core and has on its inner surface a coating of pressure sensitive, permanently tacky adhesive, is mounted on the roll so that it is slidable therearound during unwinding of a predetermined or desired length of tape, comprises an outer part in sliding engagement with the outermost tape convolution and an inner part in sliding engagement with the inner periphery of the core, and embodies on its outer part a transversely extending serrated or tooth-equipped edge whereby the inner or attached end of the unwound length may be cut from the remainder of the tape in roll form around the core.

One object of the invention is to provide a tape cutting device of this type which is an improvement upon, and has certain advantages over, previously designed devices for the same purpose and is characterized by the fact that the outer and inner parts thereof are connected together by elastic means in order that the outer part is automatically pulled or drawn towards the inner part as the size of the roll progressively decreases in connection with removal of lengths of tape.

Another object of the invention is to provide a tape cutting device of the last mentioned character in which the elastic means for holding and connecting the outer and inner parts together is in the form of an ordinary rubber band which has its side portions operatively connected to one of the parts and its rounded end portions operatively connected to the other part.

A further object of the invention is to provide a tape cutting device which is generally of new and improved construction, effectively and efficiently fulfills its intended purpose and is so designed that it may be produced at an extremely low cost and after use on one roll of tape may be readily applied to and used on another roll of tape.

Other objects of the invention and the various advantages and characteristics of the present cutting device will be apparent from a consideration of the following detailed description.

The invention consists in the several novel features which are hereinafter set forth and are more particularly defined by claims at the conclusion hereof.

In the drawing which accompanies and forms a part of this specification or disclosure and in which like numerals of reference denote corresponding parts throughout the several views:

2

Figures 1 and 2 are, respectively, top and bottom perspective views of a tape cutting device embodying one form of the invention;

Figure 3 is a side view showing the cutting device of Figures 1 and 2 applied to a roll of tape and illustrating the manner in which the serrated edge on the upper part of the device operates to sever or cut the inner end of an unwound length of tape;

Figures 4 and 5 are, respectively, top and bottom perspective views of a tape cutting device embodying another form of the invention;

Figure 6 is a side view showing the device of Figures 4 and 5 applied to a roll of tape;

Figures 7 and 8 are, respectively, top and bottom perspective views of a tape cutting device embodying a third form of the invention; and

Figure 9 is a side view illustrating the device of Figures 7 and 8 in operative relation with a conventional roll of tape.

The device which is shown in Figures 1, 2 and 3 of the drawing constitutes one form of the invention. It is adapted for use in connection with a roll 10 of tape 11, serves as a medium for cutting unwound lengths of tape from the roll and consists of but three elements, namely, an outer part 12, an inner part 13, and an elastic connecting element 14 between the outer and inner parts. The tape roll 10 embodies an annular core

15 of stiff, comparatively thick cardboard or other suitable material and the tape 11 is wound in spiral form around the core 15 and has on its inner surface a coating of pressure sensitive, permanently tacky adhesive. When it is desired to remove a length of tape from the roll the outer end of the tape is grasped and pulled away from the core and at the same time the roll is rotated until the desired length of tape is unwound. Thereafter the inner or attached end of the unwound length is cut from the remainder of the tape constituting part of the roll 10, as well understood in the art.

The outer part 12 of the device of Figures 1, 2 and 3 is of one-piece character and preferably in the form of a sheet metal stamping and consists of a top wall 16, a front wall 17 and a rear wall 18. When the device is in its operative position as shown in Figure 3 the outer part 12 is in sliding engagement with the outer convolution of the tape 11 in order that it is capable of being moved circumferentially with respect to the roll. The outer part 12 is the same in width as the tape 11. The top wall 16 of the outer part is rectangular and flat and has its central portion deformed downwards to provide a full width, open top and ended channel 19 of U-shaped cross sec-

tion. The front wall 17 of the outer part 12 is connected to, and extends downwards and forwards from, the front margin of the top wall 16. The lower margin of the front wall is bent outwards so as to fit slidably against the subjacent portion of the outermost convolution of the tape. It is shaped to provide a serrated or tooth-equipped cutting edge 20 which extends transversely across the tape and serves as a severing medium or instrumentality for the inner 10 end of the unwound length of tape. The rear wall 18 of the outer part 12 is connected to, and extends downwards and rearwards from, the rear margin of the top wall 16 and is the same in height as the front wall. The lower margin of 15 the rear wall is bent outwards so as to fit slidably against the subjacent portion of the outer convolution of the tape.

The inner part 13 of the device of Figures 1, 2 and 3 is adapted to extend transversely across 20 and to engage slidably the inner periphery of the core 15. It is preferably formed of a one-piece sheet metal stamping and consists of an elongated flat strip 21, the ends of which are bent downwards and inwards to form a pair of opposed 25 inwardly extending hooks 22.

The elastic element 14 serves yieldingly to connect the outer and inner parts 12 and 13 of the device of Figures 1, 2 and 3. It is in the form of an ordinary rubber band and consists of side portions 23 and curved or rounded end portions 24. The intermediate parts of the side portions 23 fit within, and extend lengthwise of, the channel 19 in the central portion of the top wall 16 and the end parts of said side portions extend inwards across the sides of the tape roll 10 as shown in Figure 3. The curved end portions 24 of the rubber band that constitutes the elastic element 14 are looped around the hooks 22 on the ends of the strip 21. The length of the rubber band is such that the band, when connected in place, is under tension and hence serves to draw or pull together the outer and inner parts. When a length of tape is removed from the roll 10 as hereinbefore described the device of Figures 1, 2 and 3 slides around the roll due to the action of the tape leaving the roll. After the desired length of tape has been removed the outer part 12 is pressed firmly against the roll and the unwound length of tape is then pulled to one side so that its inner or attached end is cut by the serrated or tooth-equipped edge 20 of the lower margin of the front wall 17. The elastic element 14 operates automatically to pull or draw the outer part 12 towards the inner part 13 as the size or diameter of the roll 10 progressively decreases in connection with removal of lengths of tape (see dotted lines in Figure 3). The intermediate parts of the side portions 23 of the elastic element rest on the bottom of the channel 19 and are held against lateral displacement with respect to the outer part 12 as a result of engagement with the channel sides. By confining the intermediate parts of the side portions of the elastic element in the channel the element as a whole operates to cause the inner part 13 to slide conjointly with the outer part when the outer part is moved circumferentially with respect to the roll in connection with removal of a length of tape from the roll.

The device of Figures 1, 2 and 3 effectively and efficiently fulfills its intended purpose and, due to its construction, may be manufactured or produced at an extremely low cost. It may be applied or mounted in place with facility and is

characterized by the fact that the elastic element 14 serves automatically to draw the outer part 12 toward the inner part as the roll of tape diminishes in diameter. After the tape of the roll 10 is exhausted the device may be applied to another roll merely by unhooking one of the end portions 24 of the elastic element from its hook. This releases the outer and inner parts so that they may be withdrawn from the roll and then applied to another roll. Application of the device to a new roll of tape is effected by placing the outer part 12 against the outer convolution of the tape and the inner part against the inner periphery of the core and then looping over the hooks 22 the end portions of the rubber band that constitutes the elastic element 14.

The device which is shown in Figures 4, 5 and 6 of the drawing constitutes a second embodiment of the invention and is illustrated in connection with a tape roll 25. It serves the same purpose as, and functions similarly to, the tape cutting device of Figures 1, 2 and 3. The roll 25 is the same as the roll 10 and comprises an annular core and an elongated strip of tape which is wound spirally around the core and has on its inner surface a coating of pressure sensitive, permanently tacky adhesive. The device of Figures 4, 5 and 6, like the device of Figures 1, 2 and 3, consists of an outer part, an inner part and an elastic element. The latter are designated in the drawings, respectively, by the reference numerals 26, 27 and 28.

The outer part 26 is preferably in the form of a sheet metal stamping and consists of a bottom wall 29, a front wall 30 and a back wall 31. The bottom wall is flat and rectangular and engages slidably the outermost convolution of the tape forming a part of the roll 25. It is the same in width as the tape and has its central portion upwardly deformed in order to provide a hollow, full width rib 32. The latter is of inverted U-shaped cross section, has open ends and is disposed midway between the front and rear margins of the bottom wall 29. The front wall 30 of the outer part 26 is connected to, and extends upwards and rearwards from, the front margin of the bottom wall 29. It is disposed at approximately a 60° angle with respect to the bottom wall and has its upper margin shaped to form a serrated or tooth-equipped cutting edge 33 which extends transversely of the roll and is located an appreciable distance above the outermost convolution of the tape. The rear wall 31 of the upper part 26 is connected to, and extends upwards and forwards from, the rear margin of the bottom wall 29. It is disposed at substantially a 60° angle with respect to said bottom wall and has at its upper margin a downwardly and forwardly extending integral extension 34 which is disposed directly behind and serves to reinforce the front wall 30 against flexure in a rearward direction. When a length of tape is unwound or withdrawn from the roll 25 and then swung or folded rearwards so that its inner end extends across the serrated cutting edge 33 and the upper margin of the front wall 30 of the upper part 26 sidewise pulling of the tape will result in its inner or attached end being cut by said edge. By having the cutting edge 33 disposed at an appreciable distance from the outermost tape convolution the outer end of the tape on the roll 25, i. e., the tape end that remains after unwinding and cutting of a length of tape, extends upwards across the front wall 30 and hence forms a tab which may be readily

grasped in connection with unwinding and cutting the next length of tape from the roll. The upstanding rib 32 on the central portion of the bottom wall 29 defines with the lower margin of the front wall 30 an open top and ended full width channel 35 and forms with the lower margin of the rear wall 31 an open top and ended full width channel 36.

The inner part 27 of the tape cutting device of Figures 4, 5 and 6 extends across and engages slidably the inner periphery of the core of the roll 25 and is the same in design and construction as the inner part 13 of the tape cutting device of Figures 1, 2 and 3. It is preferably in the form of a one-piece sheet metal stamping and comprises an elongated, flat, rectangular strip 37, the ends of which are bent downwards and inwards to form a pair of opposed hooks 38.

The endless elastic element 28 serves yieldingly to connect together the outer and inner parts 26 and 27. It is in the form of an ordinary rubber band and consists of a pair of side portions 39 and a pair of curved or rounded end portions 40. The central parts of the side portions 39 are disposed within, and extend lengthwise of, the channels 35 and 36 on opposite sides of the upstanding rib 32 and the end parts of the side portions 39 extend inwards across the sides of the roll 25, as shown in Figure 6 of the drawing. The curved or rounded end portions 40 of the rubber band constituting the element 28 are looped or hooked around the hooks 38 at the ends of the strip 37. The element 28 functions in the same manner as the elastic element 14 of the cutting device of Figures 1, 2 and 3 and serves to connect the outer and inner parts 26 and 27 together for conjoint sliding movement circumferentially with respect to the roll and also automatically to draw or pull the outer part towards the inner part as the roll of tape decreases in size or diameter in connection with removal of lengths of tape therefrom. The tape cutting device of Figures 4, 5 and 6 has the same advantages and characteristics as the device of Figures 1, 2 and 3 and is the same as the last mentioned device except for the form or design of the outer part 26.

The cutting device which is shown in Figures 7, 8 and 9 constitutes a third embodiment of the invention. It is illustrated in connection with a conventional tape roll 41, functions in the same manner as the device of Figures 1, 2 and 3 and the device of Figures 4, 5 and 6 and consists of an outer part 42, an inner part 43 and an endless elastic element 44. The outer part 42 is preferably in the form of a one-piece sheet metal stamping and comprises a flat, rectangular plate 45 which when the device is in its operative position engages slidably the outermost convolution of the tape of the roll 41. The width of the plate is substantially the same as the tape. The front margin of the plate 45 is shaped to form a serrated or tooth-equipped cutting edge 46 which extends transversely across the tape and serves the same purpose as the cutting edge 20 of the cutting device of Figures 1, 2 and 3. The ends of the side margins of the plate 45 are bent upwards and inwards in order to form four inwardly extending hooks 47 at the corners of the plate. The intermediate portions of the side margins of the plate 45 are bent downwards to form depending flanges 48 which are in straddled relation with the sides of the roll of tape and serve to guide the plate in connection with movement circumferentially of the roll and also to hold the

plate against lateral or sidewise displacement with respect to the roll.

The inner part 43 extends transversely across and engages slidably the inner periphery of the core of the tape roll 41. It is preferably in the form of a one-piece sheet metal stamping and consists of a rectangular plate 49, the central portion of which is downwardly bent or deformed to form a full width, depending rib 50. The front and rear margins of the plate 49 are bent downwards and define with the sides of the rib 50 two spaced apart, open ended channels 51. The latter face downwards and have open bottoms.

The elastic element 44 is in the form of an ordinary rubber band and consists of side portions 51 and end portions 52. The intermediate parts of the side portions 51 are disposed within, and extend lengthwise of, the channels 50 and the end parts of the side portions 51 extend outwards across the sides of the tape roll 41. The end portions of the elastic element 44 extend lengthwise of the side margins of the plate 45 constituting the outer part 42 and are arranged in hooked or looped relation with the upwardly and inwardly extending hooks 47 at the corners of the plate 45. The elastic element 44 serves the same purpose as the elastic element 14 of the device of Figures 1, 2 and 3 and the elastic element 28 of the tape cutting device of Figures 4, 5 and 6. It serves operatively to connect the outer and inner parts 42 and 43 for conjoint sliding movement around the roll of tape and also automatically to draw or pull the outer part toward the inner part in connection with progressive decrease in the size or diameter of the roll 41 due to removal of lengths of tape from the roll.

The device of Figures 7, 8 and 9, as heretofore indicated, functions in the same manner as the device of Figures 1, 2 and 3 and the device of Figures 4, 5 and 6. In addition, it possesses the same advantages and characteristics.

The invention is not to be understood as restricted to the details set forth since these may be modified within the scope of the appended claims without departing from the spirit and scope of the invention.

Having thus described the invention what I claim as new and desire to secure by Letters Patent is:

1. As a new article of manufacture, a device designed for use in connection with an open center roll of tape, adapted when a length of tape is unwound from the roll and properly manipulated with respect to the device to cut the inner end of the length, and comprising an outer part extending across, and circumferentially and bodily slidable on, the outermost convolution of the tape and provided with a tape cutting edge, an inner part extending across, and circumferentially and bodily slidable on, the inner periphery of the roll, one of the parts having an open ended channel formation formed therein and extending completely thereacross and from one side of the roll to the other, and the other of said parts being provided adjacent the sides of the roll with opposed hooks and elastic means extending between the two parts, arranged to connect said parts together for conjoint sliding movement relatively to the roll and also automatically to pull or draw the outer part towards the inner part as the roll decreases in size due to removal of lengths of tape therefrom, and consisting of a single rubber band embodying side portions and end portions between the ends

of the side portions and having the intermediate parts of its side portions disposed within, extending lengthwise through, and in laterally interlocked relation with, the channel formation of the one part, the end parts of said side portions extending substantially radially across the sides of the roll, and its end portions looped around, and detachably connected to, the hooks of said other part.

2. As a new article of manufacture, a device designed for use in connection with an open center roll of tape, adapted when a length of tape is unwound from the roll and properly manipulated with respect to the device to sever the inner end of the length, and comprising an outer part extending transversely across, and circumferentially and bodily slidable on, the outermost convolution of the tape, provided with a tape cutting edge at its front portion, and having formed therein an open ended, full width channel formation, an inner part extending across, and circumferentially and bodily slidable on, the inner periphery of the roll and provided adjacent the sides of the roll with opposed hooks, and elastic means extending between the two parts, arranged to connect said parts together for conjoint sliding movement relatively to the roll and also automatically to pull or draw the outer part towards the inner part as the roll decreases in size due to removal of lengths of tape therefrom, and consisting of a rubber band having the intermediate parts of its side portions disposed in, extending longitudinally through, and laterally interlocked with, said channel formation in the outer part, the end parts of said side portions extending radially inwards across the sides of the roll, and its end portions looped around the hooks on the inner part.

3. As a new article of manufacture, a device designed for use in connection with an open center roll of tape, adapted when a length of tape is unwound from the roll and properly manipulated with respect to the device to sever the inner end of the length, and comprising an outer part extending across, and circumferentially and bodily slidable on, the outermost convolution of the tape and embodying a top wall spaced from said outermost convolution and having formed therein a depending, open ended, full width channel, a front wall connected to, and extending downwards and forwards from, the front margin of the top wall and provided

at its lower margin with a tape cutting edge, and a rear wall connected to, and extending downwards and rearwards from, the rear margin of the top wall, an inner part extending across, and circumferentially and bodily slidable on, the inner periphery of the roll and provided adjacent the sides of the roll with opposed, inwardly extending hooks, and elastic means extending between the two parts, arranged to connect said parts together for conjoint sliding movement relatively to the roll and also automatically to pull or draw the outer part towards the inner part as the roll decreases in size due to removal of lengths of tape therefrom, and consisting of a rubber band having the intermediate parts of its side portions disposed within, and extending lengthwise through, the channel, the end parts of said side portions extending inwards across the sides of the roll and its end portions looped around, and detachably connected to, the hooks on the inner part.

4. A new article of manufacture as defined in claim 1 wherein the outer part is provided with a bottom wall positioned in sliding engagement with the outermost convolution, which wall has said open ended channel formation therein and extending completely thereacross, a front wall connected to, and extending upwards and rearwards from, the front margin of the bottom wall and provided at its upper margin with a tape cutting edge, and a back wall connected to and extending upwards from, the rear margin of the bottom wall and wherein the inner part is provided adjacent the sides of the roll with opposed inwardly extending hooks.

5. A new article of manufacture as described in claim 1 wherein the outer part comprises a substantially flat plate positioned tangentially with respect to the roll, which plate is provided with upwardly and inwardly extending hooks located adjacent to its side margins, and wherein in the inner part is provided with said open ended channel formation formed therein and extending thereacross from one side of the roll to the other.
